UNITED STATES PATENT OFFICE.

ROBERT C. BENDER, OF ST. LOUIS, MISSOURI.

INVOICE-HOLDER.

1,256,866.

Specification of Letters Patent. Patented Feb. 19, 1918.

Application filed July 5, 1917. Serial No. 178,675.

To all whom it may concern:

Be it known that I, ROBERT C. BENDER, a citizen of the United States, residing at St. Louis, Missouri, have invented a certain new 5 and useful Improvement in Invoice-Holders, of which the following is a full, clear, and exact description, such as will enable others skilled in the art to which it appertains to make and use the same, reference being had 10 to the accompanying drawings, forming part of this specification.

My invention relates to an invoice holder, the principal object of my invention being to provide a comparatively simple, inexpensive 15 holder which is adapted to receive and hold in a convenient manner invoice sheets or slips such as are usually employed by business houses and particularly those engaged in the selling and distributing of 20 merchandise.

A further object of my invention is to provide a holder to which the invoice sheets can be easily and quickly applied or from which they can be readily removed, said invoice 25 sheets being retained upon the holder in such a manner as to permit portions of the sheets to be readily raised or folded over in order to show certain data on the lowermost invoice sheets, this provision being essential 30 in order to facilitate the work of the bookkeeper or clerk in making out the customer's statements and in checking off the cash receipts, bills payable and the like. After being removed from the holder, the 35 invoices are placed in suitable containers and constitute a permanent record.

With the foregoing and other objects in view, my invention consists in certain novel features of construction and arrangement of 40 parts, hereinafter more fully described and claimed, and illustrated in the accompanying drawings, in which—

Figure 1 is a front or face view of an invoice holder of my improved construction 45 and showing an invoice sheet or slip in position thereupon;

Fig. 2 is an elevational view of the rear side of the holder;

Fig. 3 is an edge view of the holder; and 50 Fig. 4 is a detail end elevation of the holder and showing portions of the invoice

sheets thereupon turned upward in order to disclose the portions of the faces of the lowermost sheets.

Referring by numerals to the accompanying drawings, 10 designates the body of my improved holder, the same being formed of a rectangular section or sheet of comparatively thin material such as cardboard, and formed in the lower portion thereof is a 60 centrally arranged arcuate slot 11, the same being disposed so as to form an upwardly presented tongue 12.

Positioned on the front face of the extreme lower portion of the body 10 is a 65 transversely disposed strip 13 of metal, the same being secured to the body 10 in any suitable manner, preferably by means of rivets 14, and formed integral with the central portion of this metal strip is an upwardly projecting tongue or finger 15. This tongue or finger extends beneath a transversely disposed strip 16 which is formed by slotting the tongue 12 and immediately above this strip the tongue or finger is bent 70 outwardly as designated by 17 and thence upwardly and the upper end of said tongue or finger is pressed inwardly to form a boss or projection 18 which normally bears with yielding pressure directly against the face of 75 the body 10 or against the invoice sheet positioned thereupon.

By bending the tongue or finger outwardly as designated by 17, the upper portion of the body of said tongue or finger is spaced apart 80 from the body of the holder which provision permits a number of invoice sheets to be positioned upon the holder without exerting any wedging action upon the tongue.

Positioned on the central portion of the rear face of the body 10 is a longitudinally disposed strip 19, preferably of metal, the same acting as a stiffening device and reinforcing member for said holder, the lower end of said strip being fixed to the body of 90 the holder by means of a staple 20 or the like, which latter is seated in the central portion of strip 13. The upper end of this reinforcing strip 19 is secured to the upper portion of body 10 by means of a rivet 20 or the like 95 and pivotally secured to said rivet and disposed on the front face of the holder is a 100

keeper 21, the body of which is bent outwardly as designated by 22 immediately beneath the rivet 20, and the lower end of this keeper is depressed to form a boss 23 which bears directly against the face of the body 10 or against the invoice sheet positioned thereupon.

Formed in the side edges of the body 10 a short distance below the top thereof are 10 notches 24 which are adapted to serve as seats for an elastic band 25 which latter can be readily applied to or removed from the holder and which can be used for retaining the side edges of the invoices flat against the 15 holder while the latter is temporarily out of use, and filed away in a suitable holder or cabinet.

To place an invoice sheet on my improved holder, the keeper 21 is turned laterally and 20 upwardly to the position illustrated by dotted lines in Fig. 1, and the upper end of the resilient tongue 15 is now engaged and pulled away from the face of the holder, which action will pull the upper portion of tongue

25 12 outwardly with respect to the plane occupied by the body of the holder, thus enabling the lower edge of the invoice sheet A to be inserted behind the tongue or finger and into the arcuate slot 11.

30 Tongue or finger 15 is now released, thereby permitting the same and the tongue 12 to resume their normal position and in so doing, the lower central portion of the invoice sheet will be firmly gripped and held in 35 proper position upon the face of the holder. The keeper 21 is now swung downwardly into position over the upper edge of the invoice sheet and thus said sheet will be conveniently held until the order covered by 40 said invoice sheet is disposed of and until the proper data from said sheet are transferred to proper books or record sheets.

In the event that there are a number of 45 invoices for one customer and which possibility is very likely to occur where a business house has a number of regular customers making several purchases per day, week or month, the additional invoices can be successively placed on the holder and when the 50 bookkeeper or proper clerk desires to transfer the accounts on the various invoices to the proper books, it will be a comparatively easy matter to examine those invoices below the uppermost one by simply turning up or 55 bending over either the right or left hand portion of the invoices, as illustrated in Fig. 4.

The rear portion of the body of the holder can be printed with suitable headings for 60 data relative to the customers whose invoices are placed on the holder, such headings being illustrated in Fig. 2.

When a number of invoice sheets are

placed on a holder and the latter is temporarily out of service and placed in a suitable cabinet or container, an elastic band is slipped over the upper portion of the body and the invoice sheets thereon, said band being seated in the notches 24 and thus the sides of the invoice sheets are held flat upon the holder so that they will not tend to become torn or folded inwardly.

An invoice holder of my improved construction is comparatively simple, can be easily and cheaply manufactured, and provides an efficient and convenient time and labor saving device for all business houses using invoice sheets and the like.

It will be readily understood that minor changes in the size, form and construction of 80 the various parts of my improved invoice holder can be made and substituted for those herein shown and described, without departing from the spirit of my invention, the scope of which is set forth in the appended 85 claims.

I claim:

1. In a device of the class described, a body, a resilient tongue on the lower portion of the face of said body, a keeper pivotally mounted on the upper portion of the face of said body, and a centrally arranged reinforcing strip on the rear face of said body.

2. In a device of the class described, a body, a resilient tongue on the lower portion of the front face of said body, and there being notches formed in the side edges of said body near the upper end thereof.

3. In a device of the class described, a body, a resilient tongue on the lower portion of the front face of said body, there being notches formed in the side edges of said body near the upper end thereof, and a pivotally mounted keeper on the upper portion 105 of the face of said body.

4. In a device of the class described, a body formed of thin sheet metal, there being an arcuate slot formed in the lower central portion of said body, which slot is arranged 110 so that the material below it forms an upwardly projecting tongue, and there being notches formed in the side edges of the upper portion of said body, which notches are adapted to provide seats for an elastic member.

5. In a device of the class described, a body formed of comparatively thin sheet material slotted near its lower end to form an upwardly projecting tongue, a tongue 120 of resilient material connected to said first mentioned tongue and extending upwardly against the front face of the body, and a keeper pivotally mounted on the front face of the upper portion of said body.

6. In a device of the class described, a

body formed of comparatively thin sheet material slotted near its lower end to form an upwardly projecting tongue, a tongue of resilient material connected to said first mentioned tongue and extending upwardly against the front face of the body, a keeper pivotally mounted on the front face of the

upper portion of said body, and there being notches formed in the side edges of the body near the upper end thereof.

10

In testimony whereof I hereunto affix my signature this 3d day of July, 1917.

ROBERT C. BENDER.
